APPARATUS FOR MAKING WOOD PULP CHIPS

Edward M. Key, McMinnville, Oreg., assignor of one-half to Herbert B. Fischborn, Portland, Oreg.

Application September 23, 1957, Serial No. 685,491

3 Claims. (Cl. 144—162)

This invention pertains to wood chippers, and relates particularly to a method and apparatus for producing wood pulp chips from a portion only of rough cut lumber.

It is generally recognized throughout the sawmill industry that considerable waste of lumber occurs during the final planing operation which reduces lumber to precise dimensions and smooth surfaces. Such waste includes not only excessive loss of high grade wood due to the initial cutting of the rough lumber to sizes substantially exceeding the finished dimensions, but also includes the waste of power which is required of the planer for removing this excess wood. Thus, the sawmill is burdened with the excessive expense of providing planer motors of excessive horsepower and accordingly excessive initial cost and operating expense, in order to reduce the excess dimensions of high grade lumber to shavings which are useful only as hog fuel or as low priced material for certain types of particle board.

On the other hand, it is recognized that wood chips of a specified character command a premium price for use in the manufacture of pulp and paper. However, the manufacture of wood pulp chips of the required specifications heretofore has been achieved by means of conventional wood chippers which function to consume the entire mass of wood fed to them. Thus, conventional chippers do not solve the problem of salvaging the excess dimensions of lumber in the form of high grade wood pulp chips.

Accordingly, it is a principal object of the present invention to provide a method and apparatus by which the excess portion only of the dimensions of rough cut lumber may be reduced to wood pulp chips of high quality.

Another important object of this invention is the provision of apparatus for reducing a portion only of the dimensions of lumber to high quality wood pulp chips, which apparatus is adaptable for installation and operation immediately adjacent the infeed end of a lumber planer.

A further important object of the present invention is the provision of apparatus which is adjustable to effect removal of varying proportions of the dimensions of lumber in the form of high quality wood pulp chips of varying dimensions.

Still another important object of this invention is to provide apparatus for producing wood pulp chips, which apparatus is of simplified and sturdy construction for economical manufacture and long operating life, and which may be maintained and repaired with facility and speed.

The foregoing and other objects and advantages of this invention will appear from the following detailed description, taken in connection with the accompanying drawing, in which:

Figure 1 is a fragmentary foreshortened schematic view in side elevation of a sawmill planer having installed adjacent the infeed end thereof apparatus for making wood pulp chips, embodying the features of the present invention;

2

Figure 2 is a fragmentary foreshortened plan view of a chipper head assembly embodying the features of the present invention;

Figure 3 is a sectional view taken along the line 3—3 in Figure 2;

Figure 4 is a sectional view taken along the line 4—4 in Figure 2; and

Figure 5 is an enlarged fragmentary view in side elevation illustrating the chipping operation of the chipper head assembly illustrated in Figures 2, 3 and 4.

As indicated hereinbefore, the apparatus of this invention is particularly adaptable for use immediately adjacent the infeed of a sawmill planer. In the schematic view of Figure 1 there is illustrated a planer head 10 associated with a planer table 12, resilient hold-down members 14 and two pairs of infeed rolls 16, 18. Usually the planer head is driven from one source of power and the infeed rolls from another source of power, with all of the feed rolls interconnected in any desired manner, for synchronous operation. Lumber 20 is fed to the planer head from a conventional feed table such as is illustrated by the plurality of driven rolls 22. The planer head rotates in the direction opposite the direction of movement of lumber, as indicated by the arrow, to remove the excess wood in the form of shavings.

In accordance with the present invention, the wood pulp chipping apparatus is interposed between the feed table rolls and the planer infeed rolls. Thus, as illustrated in Figure 1, there is provided a chipper head 24 associated with a chipper table 26, a resilient hold-down member 28 and a vacuum hood 30 for removing the chips to a place of storage. A pair of chipper infeed rolls 32 and a pair of chipper outfeed rolls 34 are located at appropriate opposite sides of the chipper head, as illustrated. These pairs of feed rolls preferably are connected to the planer infeed rolls for synchronous operation, to assure uniformity of feed of lumber through the assembly.

Referring now particularly to Figure 2 wherein is illustrated one form of chipper head embodying the features of this invention, an elongated chipper knife support 36 is provided with end shafts 38 adapted to be mounted in bearings upon a suitable frame for axial rotation, being driven by a suitable source of power. The end shafts may be formed as an integral part of the knife support, or may constitute a single shaft extending through an axial bore in the knife support, with the latter being secured to the shaft by means of the key 40 illustrated, or by other conventional means.

The chipper head construction illustrated in the drawing is designed to accommodate removal of wood pulp chips from the top surface and one side surface of a piece of lumber. Accordingly, the chipper knife support 36 includes an end section 42 of larger cross-sectional dimension. In the embodiment illustrated, both sections of the knife support are square in cross section, although other shapes, e.g. triangular or polygonal, may be employed if desired, as explained more fully hereinafter.

A plurality of chipper knives are adapted to be mounted securely upon the elongated section 36 of the knife support. In the illustrated embodiment each knife includes a cutting section 44 and a shank section 46 provided with a longitudinal slot 48 adapted to receive one or more securing bolts 49 which may be threaded into tapped openings in the knife support. Although the knives may be arranged in various patterns upon the support, the arrangement illustrated is as follows: Two knives are positioned on the elongated section 36 immediately adjacent the enlarged end section 42, diametrically opposite each other. A second pair of knives is positioned on the elongated knife support adjacent the first pair, diametrically opposite each other and displaced 90° from the first

pair. Additional pairs of knives are mounted on the elongated section of the support successively toward the end of the latter opposite the enlarged end section 42 and displaced 90° from the preceding pair.

Each of the knives mounted on the elongated support is bent obliquely intermediate its ends and is provided with a cutting edge 50. The back edge of the knife tapers to the cutting edge, preferably arcuately in order to provide maximum strength adjacent the cutting edge. In order to provide a slicing action as the knife cuts through wood, the cutting section of the knife preferably is twisted slightly on its longitudinal axis and the side edges and cutting edge ground to permit engagement of the cutting edge with the wood progressively from one side to the other. Thus, the width of the knife varies to achieve this result, but the side edges generate parallel planes during rotation and the cutting edge generates a cylinder during rotation.

Referring particularly to Figure 4 of the drawing, the knives supported on the elongated section 36 are arranged in such manner that a radial line drawn from the axis of rotation of the cutter head to the cutting edge of the blade forms with the adjacent surface of the blade an acute angle A not substantially less than 50°. This is an important requirement of the present invention for the production of wood pulp chips of acceptable quality. If this angle is substantially less than 50° the trailing end of the chip becomes broken as it is removed from the lumber, thereby fracturing the wood fiber and rendering the chips useless for pulp purposes. The angle may be increased as the ratio of lumber feed rate to chipper head speed is increased, in order to prevent pressure contact of the back surface of the knife against the adjacent wood surface, as explained more fully hereinafter.

It has been determined that the most suitable pulp chips are produced when the aforementioned angle is about 68°. Although the manner in which said chips are produced is not completely understood, it is believed that as each knife is driven arcuately into the wood by rotation of the cutter head, the knife edge cuts arcuately 40 downward and forward while the leading surface of the knife adjacent the cutting edge functions as a wedge to pry off the wood in front of the knife. In any event, it has been determined that the operation of the cutter head functions to produce thin wood chips 52 having beveled ends and a maximum width equal to the width of the knife. The thickness of the chip is dependent somewhat upon the thickness of wood being removed from the lumber. When the thickness of wood being removed is less than about $\frac{1}{8}$ inch, the chip is the same thickness. On the other hand, when the thickness of wood being removed is greater than about $\frac{1}{8}$ inch, the chips are removed in layers of about $\frac{1}{8}$ inch, as is illustrated in Figure 5.

A critical requirement for wood pulp chips is that they be of a predetermined length, i.e. the length between the beveled ends. Since this length varies for different types of pulp products, means is provided in the method and apparatus of this invention for adjusting the length of chips to be produced. The preferred manner of adjustment involves the variation of the rate of speed with which the lumber 20 is fed past the chipper head 24, with the latter being rotated at a constant speed. This may be accomplished conveniently by providing a variable speed source of power for the feed rolls. It will be understood that, with the chipper head being driven at a constant speed, the length of the chips will vary in proportion to the rate of feed of lumber past the chipper head.

Alternatively, it will be apparent that the length of chips may be varied by maintaining the rate of speed of lumber past the chipper head at a constant rate, and varying the rotational speed of the chipper head. Further variation may be made by providing the chipper head with fewer or greater numbers of knives, as for example by providing a knife support having a triangular

cross section or a polygonal cross section, with each face supporting a knife.

It is important further to the production of high quality wood pulp chips that the forward feed rate of the lumber past the chipper head be less than the speed with which the chipper knife travels forwardly through the wood. It is apparent that if the rate of lumber feed is greater than the forward travel of the knife through the wood, the wood will be forced against the trailing surface of the knife with sufficient pressure to compress and damage the leading beveled end of the subsequent wood chips. It is preferred that the forward rates of speed of the lumber and the chipper knife be such that a space be maintained between the trailing surface of the knife and the adjacent surface of wood. This is accomplished in part by maintaining the forward rate of speed of the knives greater than the forward rate of lumber feed, and in part by the angle A. Obviously, the greatest circle generated by rotation of the knives must be at the cutting edge 50, and this determines the maximum magnitude of the angle A.

As explained hereinbefore, it may be desirable also to reduce the width of lumber approximately to its finished dimension, in which case there is provided the enlarged end section 42 of the knife support and the plurality of knives mounted thereon, there being two such knives illustrated in the drawing. These knives are arranged to cut completely through the thickness of the lumber and to remove such excess wood in the form of pulp chips. These knives extend radially outward from the axis of rotation of the knife support, a distance greater than the knives supported on the elongated section 36. Each of the knives is provided with a cutting section 54 and a shank section 56 having a longitudinal slot 58 for the securing bolt 59. Each knife is provided with a cutting edge 60 along a portion of the inner longitudinal edge, and a forward cutting edge 62, as illustrated. As explained hereinbefore, these latter knives function to reduce the excess dimension of lumber along one longitudinal edge to high quality wood pulp chips, and hence the knives are bent to the angular requirement explained hereinbefore.

The operation of the chipper head is best illustrated by reference to Figure 5, wherein one of the chipper knives 44 is shown in a position intermediate its path of arcuate travel through the desired thickness of lumber, the direction of forward movement of the knife and lumber 20 being indicated by arrows. As the knife penetrates further into the wood the front surface of the knife functions as a wedge to pry off the wood in front of the knife, the rate of forward travel of the knife being at least as great and preferably greater than the speed of forward travel of the lumber. Since the knife penetrates the lumber to a depth greater than about $\frac{1}{8}$ inch, the chips 52 are formed by splitting of the wood in front of the knife, in successive layers of about $\frac{1}{8}$ inch thickness.

The cutting edge of the knife preferably is slightly dulled, to prevent removal of wood at the final depth of the cut in the form of a thin shaving which is unsuitable for pulp. By so dulling the knife edge, the latter slides over the surface of the lumber without removing the final thickness thereof. Although the surface of the lumber thus acted upon by the knives has a slightly rippled surface, this is removed during the subsequent planing operation wherein the lumber is reduced to its desired finished dimensions with a minimum loss of wood in the form of shavings.

To illustrate the foregoing, a typical installation was made wherein the radius of rotation of the cutting edges 50 of the knives was $2\frac{1}{2}$ ", the angle A was 68° and the rotational speed of the cutter head 24 was set at 3600 r.p.m. With chipper knives spaced in the manner illustrated in the drawing, i.e. in pairs positioned diametrically opposite each other, high quality wood pulp chips $\frac{1}{2}$ " in length were produced with a lumber feed rate of 300 lineal feet per minute. With a triangular knife sup-

port and three knives positioned 120° apart, the feed rate of the lumber was increased to 450 feet per minute to provide the same chip. With four knives spaced 90° apart, the $\frac{1}{2}$ " chip was produced with a lumber feed rate of 600 feet per minute, and a proportionate increase in lumber feed rate is required with the use of additional knives. The angle A also was increased as lumber feed rate was increased, in order to maintain clearance between the back surface of the knife and the adjacent wood.

Thus, the present invention provides simplified apparatus by which to produce wood pulp chips of high quality and uniform standard. Although it may be utilized to produce wood pulp chips by consuming the entire board, it is particularly adaptable for use immediately adjacent the infeed end of a planer, for producing high quality wood pulp chips from the excess dimensions only of rough cut lumber, thereby effecting a considerable saving in sawmill operation.

It will be apparent to those skilled in the art that various changes in size, shape and other details of construction described and illustrated herein may be made without departing from the scope and spirit of the invention. Accordingly, it is to be understood that the foregoing description is primarily illustrative of the invention and is not to be considered as limiting the scope thereof.

Having now described my invention and the manner in which the same may be used, what I claim as new and desire to secure by Letters Patent is:

1. Apparatus for making chips of predetermined length from wood, comprising feed means for feeding wood along a line at a predetermined rate of speed, a rotary chipper head having a chipper knife mounted thereon, the knife being arranged with its leading face forming with the radial line of rotation of the cutting edge of the

knife an included angle of at least 50° , the chipper head being mounted relative to the feed means such that a predetermined thickness of wood is intercepted by the knife through an arc of rotation of the latter, the chipper head being rotatable in the direction for movement of the knife through said arc in the direction of said feed of wood and at a speed of rotation for movement of the knife through said arc at a predetermined speed greater than said feed of wood.

- 10 2. Apparatus for making chips of predetermined length from a portion of the dimensions of lumber, comprising feed means for feeding lumber along a line at a predetermined rate of speed, an elongated rotary chipper head having a plurality of longitudinally spaced knives mounted thereon, each knife being arranged with its leading face forming with the radial line of rotation of the cutting edge of the knife an included angle of at least 50° , the chipper head being mounted relative to the feed means such that a predetermined thickness of lumber is intercepted by the knife through an arc of rotation of the latter, the chipper head being rotatable in the direction for movement of the knife through said arc in the direction of said feed of lumber and at a speed of rotation for movement of the knife through said arc at a predetermined speed greater than said feed of lumber.
- 15 20 25 3. The apparatus of claim 2 including an end knife section on the chipper head arranged to cut entirely through the lumber adjacent one longitudinal edge and to remove said lumber in the form of chips.
